UNITED STATES PATENT OFFICE.

NORMAN S. MC EWEN, OF NASHVILLE, TENNESSEE.

CAN OPENER.

Application filed August 19, 1921. Serial No. 493,628.

To all whom it may concern:

Be it known that I, NORMAN S. MC EWEN, a citizen of the United States, residing at Nashville, in the county of Davidson and State of Tennessee, have invented certain new and useful Improvements in Can Openers; and I do hereby declare the following to be a full, clear, and exact description of the invention, such as will enable others skilled in the art to which it appertains to make and use the same.

This invention relates to can openers and has for its object to provide a device of this character which will be simple in construction, comparatively inexpensive to manufacture and more efficient in use than those heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views:

Figure 1 is a plan view partly broken away of a can opener made in accordance with the present invention;

30 Figure 2 is a side elevational view of the parts shown in Figure 1;

Figure 3 is a transverse sectional view, on an enlarged scale, taken on the line 3—3 of Figure 1; and

35 Figure 4 is a detail perspective view of the cutting member.

1 and 2 indicate handle members preferably shaped substantially as shown, pivotally connected together at one of their ends 40 by a bolt or rivet 3 and normally held in divergent position, as shown, by a leaf or other spring 4, secured to the said member 1 and taking against the other member 2, as will be readily apparent. Rigid with 45 the member 1 is the blade or cutting member 5 having the bevelled curved cutting edge 6 and the bevelled straight cutting edge 7 meeting in a point 8. Rigid with the member 2 is a block or anvil member 50 10 of such dimensions and so positioned as to lie substantially above the cutting member 5 when the members 1 and 2 are brought together as will be clear from Figure 2.

It will be noted from the said figure that 55 there is a clearance space 11 between the face 12 of the block 10 and the cutting blade

5, and that these two members do not act as a shear, but that the entire cutting is performed by the blade 5. That is to say, in using the present invention, the parts being in the position shown in Figure 1, the anvil member 10 is brought down inside the crimped bead 15 of the can to be opened, with the surface 12 of the said member engaging the top 16 of the can and its corners 13 and 14 engaging the said bead.

The handle members 1 and 2 are now gripped and forced together against the action of the spring 4, whereupon the member 10 taking against and supporting the bead 15, the point 8 of the cutting member 5 will penetrate the side wall 17 of the can. The latter is then grasped and rotated in a clockwise direction, as indicated by the arrow in Figure 1, thus bringing successive 75 portions of the said wall 17 into contact with the cutting edge 6 until the top or head 16 together with the crimped bead 15 is completely severed from the body of the can.

Due to the rigid construction of the parts 80 and to the fact that the anvil or guide member 10 rests against both the top 16 and the bead 15 of the can, an unusually clean and even cut is produced. Further, there is no inturned lip left on the opened can to 85 catch and retain portions of the contents thereof, as is the case when the cut is made in the top and not in the side walls of the can.

The cutting blade 5 and the anvil 10 are 90 here shown as separate pieces, secured to the handles 1 and 2 respectively by the pins or rivets 20 and 21; but if desired the parts 5 and 10 may be made integral with their respective handle members by a drop forging 95 method or in any other suitable manner.

It is obvious that those skilled in the art may vary the details of the construction as well as the arrangement of parts without departing from the spirit of the invention, 100 and therefore, I do not wish to be limited to the above disclosure except as may be required by the claims.

What I claim is:

1. In a device of the class described, the combination of a pair of pivoted handle members; means carried by one of said handle members provided with a flat surface adapted to engage the flat top of a can and with a curved surface adapted to engage a 110 portion of the inside rim of said can and to serve as a guide; and means carried by

the other of said handle members adapted to move parallel to said flat surface to cut from the outside through a wall of said can adjacent said guide means and below said top, substantially as described.

2. In a device of the class described the combination of a pair of pivoted handle members; a block rigid with one of said handle members adapted to engage the 10 crimped bead of a can cover and said cover to serve as a guide; means rigid with the

other of said handle members provided with a penetrating point and a curved cutting edge, respectively adapted to penetrate and cut in a direction from the outside and parallel to said cover a wall of the can adjacent said block; and resilient means associated with said handle members normally maintaining said members out of their operative positions, substantially as described. 15 20

In testimony whereof I affix my signature.
NORMAN S. McEWEN.
